COMBINATION BAIT AND TACKLE KIT

Paul B. Burkett, 502 W. Main St., Dothan, Ala.

Filed June 26, 1964, Ser. No. 80,599

Term of patent 14 years

(Cl. D31—4)

FIG. 1 is a perspective view of a combination bait and tackle kit showing my new design;

FIG. 2 is a top plan view thereof; and

FIG. 3 is an end elevational view thereof.

The dominant features of my design reside in the portions shown in full lines.

The cross-sectional pattern representing a conventional fabric is understood to continue uniformly throughout the bait box area.

I claim:

The ornamental design for a combination bait and tackle kit, as shown and described.
